UNITED STATES PATENT OFFICE.

HARRY NEGBAUR, OF NEW YORK, N. Y., ASSIGNOR TO E. & J. BASS, INC., A CORPORATION OF NEW YORK.

DESIGN FOR A SALT CELLAR OR SIMILAR ARTICLE.

Application filed January 21, 1924. Serial No. 8,359. Term of patent 3½ years.

To all whom it may concern:

Be it known that I, HARRY NEGBAUR, a citizen of the United States, and a resident of the city, county, and State of New York, have invented a new, original, and ornamental Design for a Salt Cellar or Similar Article, of which the following is a specification, reference being had to the accompanying drawing, forming a part hereof.

This drawing is a side elevational view of a salt cellar or similar article.

I claim:

The ornamental design for a salt cellar or similar article, substantially as shown.

HARRY NEGBAUR.

Witnesses:

M. BRANDT,
LILLIAN SMITH.
